Attorney.

UNITED STATES PATENT OFFICE.

EDWIN M. MULLIN, OF BROOKLYN, NEW YORK.

PRIZE RING.

Application filed August 4, 1921. Serial No. 489,911.

To all whom it may concern:

Be it known that I, EDWIN M. MULLIN, a subject of the King of Great Britain, residing at Brooklyn, in the county of Kings and State of New York, have invented certain new and useful Improvements in Prize Rings, of which the following is a full, clear, and exact specification.

This invention relates to prize rings for use in boxing contests and has for its object to provide a square ring or arena in which the ropes are supported in such a way that it is impossible for the contestants to fall against or come in contact with the supports for said ropes.

A further object is to increase the yielding quality of the ropes so as to cushion any contacts therewith. Another object is to provide means for more securely fastening the ropes to their supports, thus reducing the chances of the slipping or loosening of said ropes. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is a plan view of a prize or boxing ring constructed substantially in accordance with this invention.

Figure 2 is a sectional view on the line II—II of Figure 1.

Figure 3 is a detailed side view of a modified form of post fastening means, and

Figure 4 is a plan view of the same.

The platform 1 may be constructed of concrete, wood, or any other suitable material, and may be of the regulation dimensions, or somewhat larger in order to support the posts at a distance from the crossing points of the ropes. Eight posts 2 are employed, two for holding the ropes at each side of the ring. Said posts are preferably set in the platform at an incline, in order to increase the distance from their upper ends to the crossing points of the ropes.

Each post has a plurality of passages 3 formed therein, the same being preferably bored substantially at right angles to the sides of the post so that said passages are

arranged at an incline when the posts are set in position, as best illustrated in Figure 2. The mouths of the passages 3 are slightly flared and rounded, as at 4, to prevent cutting the rope 5, which is passed back and forth from one post to the other of each pair for forming the barrier at one side of the ring. One end of the rope 5 may be knotted at 6 to secure it in one of the passages 3, and said rope may then be passed back and forth between the posts, as illustrated in Fig. 2, the other end portion of said rope being securely fastened to a cleat 7 on the platform 1, or otherwise securely fastened. Because of the inclination of the passages 3, the rope has a binding action on the ends or mouths of said passages which tends to clamp said rope and prevent the same from slipping. This is especially true where the rope is looped through two adjacent passages 3, there being four bearing points for the ropes at these places, as indicated at 8 in Figure 2.

Each pair of posts, for supporting the rope barrier at each side of the ring, is arranged in line with its rope barrier, although they are inclined in opposite directions transversely thereto. As a result of this arrangement, the rope barriers at each side of the ring cross one another at 9 to form the corners of the ring, said crossing points being spaced a considerable distance from the adjacent posts, so that it is impossible for a contestant to come in contact with said posts, even though he should forcibly come in contact with the ropes at their crossing points. Moreover, owing to the extension of the ropes beyond the corners of the ring, they are adapted to yield, as indicated in dotted lines at the right hand upper corner of Figure 1, so as to cushion any contact of a contestant therewith at their crossing points.

As illustrated in Figures 3 and 4, the posts 2 may be fastened to the outer faces of the platform 1 in any suitable manner instead of having their lower ends embedded in said platform. Brackets 10 may be secured to the sides of the platform by bolts or screws 11, said brackets having upper and lower arms 12 and 13 provided with openings 14 and 15, respectively, in which the posts are seated. The openings 14 and 15 are arranged out of vertical alignment so that the posts are supported thereby in inclined position. When the ropes 5 are drawn taut, the

posts are caused to bear forcibly against the ends of said openings and are thereby clamped firmly in place.

I claim:

- 5 1. The combination, with a platform, of ropes extending substantially parallel to the sides of said platform and crossing one another adjacent the corners thereof, and posts secured to the platform for supporting said 10 ropes and spaced away from the crossing points of the latter for the purpose specified.
- 15 2. The combination, with a platform, of ropes extending substantially parallel to the sides of said platform and crossing one another adjacent the corners thereof, and posts secured to the platform for supporting said 20 ropes, said posts being inclined away from the crossing points of the ropes for the purpose specified.
- 25 3. The combination with a platform, of pairs of posts secured to said platform near each corner thereof, and ropes extending between posts at adjacent corners to form barriers at the sides of the platform, said 30 ropes crossing one another to form the corners of the barrier and the crossing points of the ropes being spaced from the adjacent posts for the purpose specified.
- 35 4. The combination, with a platform, of pairs of posts secured to said platform near each corner thereof, and ropes extending between posts at adjacent corners to form barriers at the sides of the platform, said 40 ropes crossing one another to form the cor-

ners of the barrier, and said posts being inclined away from the adjacent crossing points of the ropes for the purpose specified.

5. The combination, with a post having inclined passages therein, of a flexible barrier passed through said passages and extending horizontally from the post, whereby the mouths of said passages have a clamping action upon the barrier.

6. The combination with a post having inclined passages therein, of a flexible barrier 45 looped through said passages and extending horizontally from the post, whereby the mouths of said passages have a clamping action upon said looped portion of the barrier.

7. The combination, with a post having inclined passages therein, of a flexible barrier passed through said passages and extending horizontally from the post, whereby the mouths of said passages have a clamping 50 action upon the barrier, said mouths of the passages being flared for the purpose specified.

8. The combination with a platform, of a bracket secured thereto and having spaced 55 arms provided with perforations arranged out of vertical alignment, of an inclined post seated in the perforations in said arms, and means for pressing said posts into engagement with the ends of said perforations.

In testimony whereof I have signed my name to this specification.

EDWIN M. MULLIN.
